UNITED STATES PATENT OFFICE.

CHESTER S. JENNINGS, OF BOSTON, MASSACHUSETTS, ASSIGNOR TO THE LAMSON COMPANY, OF BOSTON, MASSACHUSETTS, A CORPORATION OF NEW JERSEY.

INTERCOMMUNICATING PICK-UP SYSTEM.

1,171,207.

Specification of Letters Patent.

Patented Feb. 8, 1916.

Application filed April 24, 1914. Serial No. 834,103.

To all whom it may concern:

Be it known that I, CHESTER S. JENNINGS, a citizen of the United States, residing at Forest Hills, Boston, in the county of 5 Suffolk and State of Massachusetts, have invented certain new and useful Improvements in Intercommunicating Pick-Up Systems, of which the following is a specification.

This invention relates to carrier despatch apparatus and more especially to what is known in the art as a pick-up system. Systems of this character usually comprise a closed one way track along which carriers 10 are propelled by an endless and continuously driven cable, together with means for loading and unloading said carriers at determined points or stations.

One of the principal objects of the present 15 invention is to provide for intercommunicating service between such stations.

Another object has been to provide a system of the character in question in which there may be more sending stations than a 20 total number of graduations of the cars; and cars moreover which will pick up only when empty.

In the accompanying drawings which 25 form a part hereof and in which like characters designate like parts throughout the several views, I have exemplified a preferred construction, but as I am aware of various changes and modifications which may be made herein without departing from the 30 spirit of my invention, I desire to be limited only by the scope of the claims appended hereto.

Referring to the drawings: Figure 1 is a 35 diagrammatic elevation of a preferred form of the pick-up system. Fig. 2 is a detail elevation drawn to a larger scale, of a portion of the apparatus shown in Fig. 1 which is disposed at one of the stations. Fig. 3 is a section taken on line III—III of Figs. 1 40 and 2, but drawn to a still larger scale than said last mentioned figure. Fig. 4 is a detail plan view of a pawl guide shown in Figs. 2 and 3. Fig. 5 is a detail elevation of said guide and associate parts. Fig. 6 is a plan view of a car, and Fig. 7 is an end view of 45 said car.

The track 1 is preferably endless or continuous and may extend wherever desired in accordance with the exigencies of the 50 service. A cable 2 serves to propel cars,

broadly designated 3, along the track in the direction of the arrows shown in Figs. 2 and 3; and since cars of this description, save for certain important changes herein-after noted, are in general use, the construction of such cars will be but generally described.

The preferred carrier or car comprises a slide 4 which rides between the rails of the track 1 and has rearwardly extending therefrom an extension 5 which is preferably fixedly connected to the cable 2. To the front of the slide 4 is attached a bracket 6 between the ears 7 of which is pivoted, upon a shaft 8, a U-shaped frame or support 9 for 60 the bent wire frame 10, which preferably constitutes the lower jaw of the package or article clamp. The upper or fixed jaw 11 of this clamp projects out from the bracket 6 from points above the shaft 8, and the 65 jaws 10 and 11 are respectively provided with loops or bends 10' and 11' which serve to retain articles in position between said jaws when the latter are clamped upon such 70 articles.

Between the inwardly directed hubs 9' of the frame 9, and loosely mounted upon shaft 8, is a bent lever 12, which for convenience of illustration has been partly broken away in Fig. 6. This lever has a stop 12' which 75 is normally held in engagement with the base of the bracket 6 by a spring 13, coiled around one of the hubs 9'; one end of this spring being in engagement with a pin 14 upon the arm 12 and the other end being 80 correspondingly in engagement with the underside of the base of the bracket. Upon the other hub 9' of the movable jaw-frame 9, is mounted a considerably heavier spring 15, the ends of which respectively engage a 85 pin 16' on frame 9 and the said under side of the bracket 6. The movable jaw 10 hence 90 has a pronounced bias for its closed or upper position.

The arm 12 of each car carries a roller 16 100 which is adapted for engagement with bent strips or cams 17A, 17B, etc., disposed at points where it is desired to open the jaws of certain or all of the cars, as the case 105 may be.

Obviously as many cars may be provided as may be desired and hence, while, for example, four stations respectively designated A, B, C and D, have been shown in Fig. 1, the number of cars provided to serve 110

these stations may be considerably in excess of this number. All cars to serve a particular station have the arms 12 thereof of the same length; that is, the roller 16 will be spaced away from the shaft 8 a determined distance corresponding to that station; but, since a number of stations are to be served it is preferable to provide different cars with arms 12 of different lengths, so that the rollers 16 of such arms may engage different cam members. To distinguish between these cam elements at unloading points, they have been respectively designated 17A, 17B, 17C, 17D, and it is evident that those cars whose rollers 16 can ride upon cam 17A, will discharge at station A, while those cars whose rollers can engage cam 17B will correspondingly discharge at station B, etc.

As shown in Fig. 2, which is a detail of station A in Fig. 1, any car which unloads into the receiving shelf or receptacle 18 at said station immediately thereafter passes the group of sending pans or shelves disposed at this station. Since there are in the present case three stations to which articles may be transmitted from station A, there are preferably provided three sending pans respectively designated *b*, *c*, and *d*. Each of these pans preferably consists of an inclined frame which is adapted to support articles such as letters or other papers or packages, and the like; suitable gages or lugs 19 and 20 being provided in connection with each pan so that when a letter, for example, has been placed thereon it will be definitely positioned with respect to the aperture 21 in the pan through which rises the movable jaw of any car which co-acts with such pan. Where larger packages or articles are also to be despatched, auxiliary centering or gage lugs 22 may project upwardly from the pan surfaces; lugs 22 being spaced farther back from the corresponding openings 21 than are the lugs 19. For convenience in construction the pans of a given station may be formed integrally, as shown in Fig. 2, and said pans are suitably supported from the tracks by brackets 23; and the receiving shelves or receptacles 18 may also be correspondingly supported from the tracks by brackets 24. Adjacent each loading pan is a loading cam rod 17^a, 17^b, 17^c, etc., which corresponds to such pan. Thus, a jaw opening cam 17^b, which is adapted to actuate the operating arm of cars which discharge at station B, is shown at station A and as such a car passes this cam 17^b its operating arm is first thrown down, and, provided that operative connections are established in the manner hereinafter described between the arm 12 and the movable jaw, the latter will be swung down before it reaches the pan *b* and since the cam 17^b terminates at or is bent away substantially

opposite the middle of pan *b*; jaw 10 will rise at this point, the portions thereof adjacent the lugs 7 to which such portions are attached, passing up through the aperture 21 of the pan *b*; the lower or movable jaw thereby lifting the article to be despatched into engagement with the upper or fixed jaw 11 against which said article is clamped by said lower jaw. Correspondingly a despatching cam 17^c co-acts with the sending pan *c*; while a third cam 17^d controls the despatch of articles from pan *d*.

Referring now more particularly to Figs. 3, 6 and 7, it will be noted that there projects upwardly through substantially the center of the jaw 10 a lever or finger 25 which is loosely mounted upon a short shaft 26, and this lever is normally held in its upper or full line position, as shown in Fig. 7, by a relatively light spring 27, one end of which is attached to said lever at 27' and the other end of which is attached to the frame 9. The shaft or pin 26 is mounted in lugs 29 which project downwardly upon either side of the frame 9; shaft 26 being conveniently secured in said lugs by means of a pin 30. Also loosely mounted upon shaft 26' is a sleeve 31 from which downwardly projects a pawl 32, the function of which will be hereinafter referred to. Sleeve 31 is also provided with a lug 33 to which is attached one end of a spring 34, the other end of which is connected at 35' to the finger 25. Spring 34 normally rotates pawl 32 clockwise with respect to finger 25 until lug 33 engages a stop-lug 35 carried by the finger 25, so that the parts 32 and 25 normally occupy the positions with respect to each other in which they are shown in Fig. 7. The sleeve 31 also has upwardly projecting therefrom a lug or extension 36 which normally lies in the path of movement of a lug 37 which projects laterally from the arm 12, so that when this arm is rotated, if lug 36 is disposed as shown in Fig. 7, a downward or opening movement of the movable jaw 10 will be effected. When a package, or even a paper, which is grasped between the jaws 10 and 11, is in place upon the car, such package or paper will depress the finger 25 to its dotted line position 25' and this will rock the lug 36 into its dotted line position 36', out of the path of movement of lug 37, so that if arm 12 be actuated by any cam rod when part 25 is thus disposed, said arm 12 will merely rock idly and will not cause jaw 10 to open. Preferably at each station, however, there is disposed a pawl guide or actuating part 38 which is adapted for engagement with the pawl 32 when the latter is in its dotted line position 32'. The pawl actuating part 38 is preferably yieldingly mounted upon a bracket 39 which is connected to the tracks, a relatively stiff spring 40 serving to rotate

5 said part 38 counter-clockwise, as viewed in Fig. 4, until an arm 38' thereof is brought into engagement with a stop lug 41 upon bracket 39. Hence every car as it passes each station has its pawl 32 rocked from the dotted line position 32' of said pawl, if the pawl be in such position, over to its full line position, shown in Fig. 7, and this without disturbing the finger 25; the connection 34 between pawl 32 and said finger yielding sufficiently to prevent the finger from being forced through, for example, a sheet of paper.

10 The general operation of the system will now be described.

15 Every laden carrier destined to discharge its contents at station A, for example, will have its jaws opened as they come opposite to the receptacle 18 at said station, so that the carrier will thereafter proceed unloaded until it picks up an article from one of the sending pans at stations A, B, C or D. If such an empty carrier is approaching station C and an article at said station is to be 20 despatched to station A, it will be emplaced in the pan *a* at station C so that when the roller 16 of said carrier engages the corresponding cam rod 17^a at station C, this will cause jaw 10 to swing open and after 25 clearing the pan parts to swing closed through the opening 21 of pan *a*, thereby forcing the article up against the fixed jaw 11. This action will depress the finger 25 and thereby the pawl 32 of said carrier will 30 be displaced counter-clockwise to its dotted line position, shown in Fig. 7. As this laden car passes station D its pawl 32 will encounter the actuating part or guide 38 at said station which will momentarily throw 35 pawl 32 back to its full line position; spring 34 yielding to accommodate this action. This will align lugs 36 and 37, but there is no cam 17^a at said station D which could engage roller 16 of the carrier when at this 40 station, and hence no movement of jaw 10 with respect to the fixed jaw will take place. The positioning of lug 36 in alignment with lug 37 is, however, but momentary and spring 34 returns it to its dotted 45 line position 36', shown in Fig. 7, as soon as its pawl 32 clears the actuating guide 38. The carrier thereafter travels along track 1 until it reaches station A at which point its lug 32 is again engaged by a guide 38 to 50 throw lug 36' again into alignment with lug 37. This time there is a cam 17A adapted to engage the roller 16 of this carrier, and arm 12 will hence be rotated counter-clockwise, as viewed in Figs. 3 and 7, until its lug 37 55 engages lug 36 and by reason of such engagement and its continued counter-clockwise rotation thereafter, will open jaw 10 and deposit the letter or other article which such carrier has conveyed from station C, into the receptacle 18 at station A, for which sta-

tion said article was destined. In like manner whenever it is desired to despatch an article from any one of the stations to any other, it is merely necessary to deposit the article to be despatched in the proper sending pan which corresponds to the station to which the article is to be sent, whereupon the first empty carrier which normally unloads at the station at which said article is to be sent, which passes the station from 75 which the article is to be despatched, will automatically pick up the article from the sending pan and convey and deliver it to the receptacle 18 at the station for which the article is destined. A true intercommunicating system is hence provided and one moreover in which the action of picking up an article from any station, conveying it to any other and predetermined station and there depositing it, is absolutely automatic. 80 85

The advantage of resiliently or yieldingly mounting the pawl operating part 38 should be pointed out, since were part 38 not adapted to yield when subjected to undue pressure, breakage of the apparatus might 90 result. Of course the spring 40 should be sufficiently stiff to overcome the spring 34 and to force the pawl 32 completely over into the position in which it is shown in Fig. 7. It is preferable also to make spring 95 34 somewhat lighter than spring 27 since the only function of spring 34 is to hold the pawl 32 normally in definite relationship to finger 25, while spring 27 has to position both finger 25 and the pawl 32 which is 100 resiliently connected to the latter.

In general it will be understood that while cars with but four graduations or lengths of arm 12 are provided in the exemplified construction, various other numbers of 105 graduations may be used and, further, that a greater number of stations may be provided than there are graduations, as, for example, where it is desired to send to two stations from, let us say, six others. In this case the cars would have but two graduations which might, for example, be used upon alternate cars; and in such case, precisely like that above described, the first empty car which would unload at a determined unloading point, would pick up an article destined for said point from the sending pan corresponding to said point disposed at any one of the sending stations. 110 115

The feature of controlling the movement 120 of the jaw of a given carrier by means of a suitable jaw actuating device which can only become operative to actually open said jaw when the car is empty or when special provision is made for rendering the jaw opening means operative independently of whether the car be loaded or not, is of great importance, and it is largely by reason of this feature that the system is capable of extension to adapt it to serve a large number of 125 130

sending stations regardless of the relatively limited number of graduations normally available.

It will be noted that the extension of all 5 of the loading cams 17^b, 17^c, etc., at any given station, back to a common point is to be preferred, since when any one of these 10 cams opens the movable jaw of a carrier, such jaw must be held out of any possibility of its colliding with any part of the set of pans which are preferably integrally formed as stated above; and the jaw of any given carrier when once opened to clear the 15 pan first encountered should therefore be held open until it reaches the aperture 21 of the pan from which such carrier is adapted to lift a load.

In conclusion it may be well to more 20 particularly point out that by means of the construction shown it is made possible to have intercommunicating service between all stations up to a number equivalent to the total number of graduations on the cars; while, further, the number of stations may 25 be quite indefinitely extended provided that the points of delivery or stations to which articles may be despatched from the various despatching points, shall not exceed the practicable or limiting number of graduations.

I am aware that equivalent constructions 30 may be substituted for the pawl guide, but the latter is to be preferred upon the ground of simplicity in that it permits of the reduction 35 of the number of jaw opening cams to a minimum while at the same time permitting of the movable members upon the cars being likewise no more in number than are sufficient to effect the objects indicated.

40 Having now described my invention what I claim is:—

1. In a pick-up and delivery system for 45 messages, parcels and the like, the combination of a track having a plurality of stations therealong, with movable jaw pick-up carriers to travel on said track, means to propel said carriers, and actuating means, co-acting with said carriers and propelling means to automatically pick up an article 50 at any given station and unload said article at a predetermined other one of said stations by actuating the movable jaw of such carrier, each of said stations, from which loads may be despatched to said predetermined unloading station, having a load supporting part which, if an article be 55 emplaced thereat, will co-act with at least one of said carriers and said pick-up actuating means to the end that said article will be loaded upon said carrier and conveyed thereby to said predetermined unloading station to be there unloaded by a part of said actuating means, said pick-up actuating means having elements thereof disposed at each of 60 said despatching stations and normally 65

adapted to load any article to be despatched, upon said carrier from the supporting part at each of said stations which corresponds to said predetermined unloading stations but unadapted to co-act with already loaded 70 carriers *en route* therewith to said unloading station, each carrier having means to render ineffective the action of the said loading elements at stations which it passes while *en route* to said predetermined unloading station, said last mentioned means for any given carrier being operatively disposed when said carrier is loaded.

2. In a pick-up and delivery system for 75 messages, parcels and the like, the combination of a track having a plurality of stations therealong with carriers to travel on said track, means to propel said carriers, and actuating means co-acting with said carriers and propelling means, to automatically 80 pick-up an article at any given station and unload said article at a predetermined one of a plurality of the stations at which carriers are to be unloaded, each of said stations, from which loads may be despatched 85 to any one of said unloading stations, having load supporting parts which, if an article be emplaced thereat in any one of a plurality of determined positions each of which positions correspond respectively to 90 one of said unloading stations, will co-act with at least one of said carriers and said pick-up actuating means to the end that said article will be loaded upon said carrier and conveyed thereby to the corresponding 95 unloading station to be there unloaded by a part of said actuating means, said pick-up actuating means having elements thereof disposed at each of said despatching stations and normally adapted to load upon a 100 passing carrier any article which may be in place in one of the said determined positions but unadapted to co-act with said passing carrier if the latter be already loaded, each of said carriers having means to render 105 ineffective the action of said loading elements at stations which it passes while *en route* to a station beyond, said last mentioned means for any given carrier being operatively disposed when said carrier is 110 loaded.

3. In a pick-up and delivery system for 115 messages, parcels and the like, the combination of a track having a plurality of stations therealong with carriers to travel on 120 said track, means to propel said carriers, and actuating means, co-acting with said carriers and propelling means, to automatically pick-up an article at any given station and selectively unload said article at a predetermined one of a plurality of stations at 125 which said carriers are to be selectively unloaded, each loading station which is adapted to despatch articles to said plurality of unloading stations having thereat a plurality 130

of loading points and means to support an article to be despatched at any one of said points, each of said loading points corresponding to one of said unloading stations, 5 said pick-up actuating means comprising elements adjacent each of said loading points for loading carriers while the latter are passing said points and said carriers having means to prevent said elements from disturbing loads already in place thereon when such loaded carriers are passing said elements.

4. In a pick-up and delivery system for messages, parcels and the like, the combination of a track having a plurality of stations therealong with carriers to travel on said track, means to propel said carriers, and actuating means co-acting with said carriers and propelling means, to automatically pick-up an article at any given station and unload said article at a predetermined other one of said stations, each of said stations, from which loads may be despatched to said predetermined unloading station, 25 having a relatively fixed load supporting part which, if an article be emplaced thereat, will co-act with at least one of said carriers and said pick-up actuating means to the end that said article will be loaded upon 30 said carrier and conveyed thereby to said predetermined unloading station to be there unloaded by a part of said actuating means, said pick-up actuating means having elements thereof disposed at each of said despatching stations and normally adapted to 35 load any article to be despatched, upon said carrier from the supporting part at each of said stations which corresponds to said predetermined unloading station but unadapted to co-act with already loaded carriers *en route* therewith to said unloading station, each carrier having means to render ineffective the action of the said loading elements at stations which it passes while *en 45 route* to said predetermined unloading station, said last mentioned means for any given carrier being operatively disposed when said carrier is loaded.

5. In a pick-up and delivery system for messages, parcels and the like, the combination of a track having a plurality of stations therealong with carriers to travel on said track, each of said carriers having a pick-up element movably mounted thereon, 55 means to propel said carriers, and actuating means to control said pick-up elements and only adapted to co-act therewith to automatically load an empty carrier, as the latter passes any given station and to thereafter unload said carrier at a determined point along said track, said system having provisions to positively prevent the emplacement of a load upon an already loaded carrier.

6. In a pick-up and delivery system for

messages, parcels and the like, the combination of a track having a plurality of stations therealong with carriers to travel on said track, each of said carriers having a pick-up element movably mounted thereon, 70 means to propel said carriers, and actuating means to control said pick-up elements and only adapted to co-act therewith to automatically load an empty carrier, as the latter passes any given station and to thereafter unload said carrier at a determined point along said track, said carriers having load-controlled means to prevent the emplacement of a load upon an already loaded carrier. 75

7. In a pick-up and delivery system for messages, parcels and the like, the combination of a track having a plurality of despatching stations and at least one receiving station, carriers each having a pick-up element movably mounted thereon, means to propel said carriers along said track, and actuating cams at said despatching stations to control said pick-up elements, each carrier having a connection movably mounted 80 thereon through which said cams act upon said pick-up elements each of said connections being normally held in a position to transmit the action of said cams as the latter are encountered by the carrier upon 85 which such connection is mounted, and being normally held out of said position when said carrier is loaded, whereby to permit of the loading of empty carriers and to prevent a cam at a despatching station along 90 the line of travel of an already loaded carrier *en route* to said receiving station, from disturbing the load upon said carrier. 95

8. In a pick-up and delivery system for messages, parcels and the like, the combination of a track having a plurality of despatching stations and at least one receiving station, carriers each having a pick-up element movably mounted thereon, means to propel said carriers along said track, and actuating cams at said despatching stations to control said pick-up elements, each carrier having a connection movably mounted 100 thereon through which said cams act upon said pick-up elements, each of said connections being normally held in a position to transmit the action of said cams as the latter are encountered by the carrier upon 105 which such connection is mounted, and being normally held out of said position when said carrier is loaded, whereby to permit of the loading of empty carriers and to prevent a cam at a despatching station along the line of travel of an already loaded carrier *en route* to said receiving station, from disturbing the load upon said carrier. 110

9. In a pick-up and delivery system for

9. In a pick-up and delivery system for messages, parcels and the like, the combination of a track having a plurality of despatching stations and at least one receiving station, carriers each having a pick-up element movably mounted thereon, means to propel said carriers along said track and actuating cams at said despatching stations to control said pick-up elements, each carrier having a connection movably mounted thereon through which said cams act upon said pick-up elements, each of said connections being normally held in a position to transmit the action of said cams as the latter are encountered by the carrier upon which such connection is mounted, and being normally held out of said position when said carrier is loaded, whereby to permit of the loading of empty carriers and to prevent a cam at a despatching station along the line of travel of an already loaded carrier *en route* to said receiving station, from disturbing the load upon said carrier, and means, including a cam at said receiving station for actuating the pick-up element of loaded carriers destined for said station, to unload said carriers.
10. In a pick-up and delivery system for messages, parcels and the like, the combination of a track having a plurality of despatching stations and at least one receiving station, carriers each having a pick-up element movably mounted thereon, means to propel said carriers along said track, and actuating cams at said despatching stations to control said pick-up elements, each carrier having a connection movably mounted thereon through which said cams act upon said pick-up elements, each of said connections being normally held in a position to transmit the action of said cams as the latter are encountered by the carrier upon which such connection is mounted, and being normally held out of said position when said carrier is loaded, whereby to permit of the loading of empty carriers and to prevent a cam at a despatching station along the line of travel of an already loaded carrier *en route* to said receiving station, from disturbing the load upon said carrier, and carrier unloading means, including an unloading cam and a device to move said connection of each loaded carrier, as it arrives substantially at said receiving station, back to its first mentioned and operative position, to permit said unloading cam to unload said carrier at said receiving station.
11. In an inter-communicating pick-up and delivery system for messages, parcels and the like, the combination of a track having a plurality of stations from which articles may be despatched and to which articles may be delivered, graduated carriers each having a pick-up element movably mounted thereon, means to propel said carriers along said track, means to support an article to be despatched, in any one of a plurality of loading positions at each of said stations from which loads may be despatched to a corresponding number of receiving stations, each of said positions at a given station corresponding to a particular receiving station and to a carrier graduated to load at such position and unload at said particular receiving station, means to load and unload carriers, and means to allow an already loaded carrier to pass a station for which its load is not destined, without disturbing the load upon said carrier.
12. In an inter-communicating pick-up and delivery system for messages, parcels and the like, the combination of a track having a plurality of stations from which articles may be despatched and to which articles may be delivered, carriers each having a pick-up element and an operating arm therefor of graduated length, means to propel said carriers along said track, means to support an article to be despatched, in any one of a plurality of loading positions at each of said stations from which loads may be despatched to a corresponding number of receiving stations, each of said positions at a given station corresponding to a particular receiving station and to a carrier the operating arm of which is graduated to load at such position and unload at said particular receiving station, cams at said stations to actuate said arms to load and unload the carriers, and normally operatively disposed connections, carried by said carriers and adapted to be held in their inoperative positions by loads on said carriers, for transmitting the thrust from any given one of said cams, upon a corresponding operating arm, to the pick-up element of the carrier upon which said arm is mounted, whereby only if a carrier be unloaded and its arm be engaged by a cam, can the pick-up element of said carrier normally be operated.
13. In an intercommunicating pick-up and delivery system for messages, parcels and the like, the combination of a track having a plurality of stations from which articles may be despatched and to which articles may be delivered, carriers each having a pick-up element and an operating arm therefor of graduated length, means to propel said carriers along said track, means to support an article to be despatched, in any one of a plurality of loading positions at each of said stations from which loads may be despatched to a corresponding number of receiving stations, each of said positions at a given station corresponding to a particular receiving station and to a carrier the operating arm of which is graduated to load at such position and unload at said particular receiving station, cams at said stations to actuate said arms to load and unload

the carriers, and normally operatively disposed connections, carried by said carriers and adapted to be held in their inoperative positions by loads on said carriers, for transmitting the thrust from any given one of said cams, upon a corresponding operating arm, to the pick-up element of the carrier upon which said arm is mounted, whereby only if a carrier is unloaded and its arm be engaged by a cam, can the pick-up element of said carrier normally be operated and means at at least one of said stations for causing one of said cams at said station to actuate the pick-up element of a passing carrier regardless of whether said carrier is loaded or not.

14. In an inter-communicating pick-up and delivery system for messages, parcels and the like, the combination of a track having a plurality of stations from which articles may be despatched and to which articles may be delivered, carriers each having a pick-up element and a graduated operating part to control said element, a plurality 25 of despatching supports at each station, each support corresponding to a particular other one of said stations to which articles may be despatched from said first mentioned station, a graduated loading cam adjacent each 30 despatching support, said cams being graduated to correspond with said carriers, graduated unloading cams at said stations, and means to cause the graduated operating part 35 of a loaded carrier *en route* past any station for which the load on said carrier is not destined, to move idly when it encounters the cam at such station which actuates said part.

15. In an inter-communicating pick-up and delivery system for messages, parcels 40 and the like, the combination of a track having a plurality of stations from which articles may be despatched and to which articles may be delivered, carriers each having a pick-up element and a graduated operating 45 part to control said element, a plurality of despatching supports at each station, each support corresponding to a particular other one of said stations to which articles may be despatched from said first mentioned station, a graduated loading cam adjacent each 50 despatching support, said cams being graduated to correspond with said carriers, graduated unloading cams at said stations, means to cause the graduated operating part 55 of a loaded carrier *en route* past any station for which the load on said carrier is not destined, to move idly when it encounters the cam at such station which actuates said part, and means adjacent said unloading 60 cams for rendering nugatory the action of said last mentioned means, whereby to permit any carrier, whose operating part is controlled by the unloading cam at any given one of said stations, to unload thereat.

16. In an inter-communicating pick-up

and delivery system for messages, parcels and the like, the combination of a track having a plurality of stations from which articles may be despatched and to which articles may be delivered, graduated carriers 70 each having a movable load supporting part, a series of supports at each station adapted to present articles to be despatched to passing carriers, a series of actuating parts at each station, each actuating part 75 corresponding to a support at said station, said actuating parts at each station being graduated to selectively actuate the load supporting parts of certain of said carriers, an unloading part at each station graduated to 80 correspond with only certain of said carriers, and means, carried by said carriers and adapted to be pressed out of operative position by a load thereon, to enable an actuating part at any station to normally load a 85 corresponding carrier from the corresponding support at such station only when said carrier is empty.

17. In an inter-communicating pick-up and delivery system for messages, parcels 90 and the like, the combination of a track having a plurality of stations from which articles may be despatched and to which articles may be delivered, graduated carriers each having a movable load supporting part, 95 a series of supports at each station adapted to present articles to be despatched to passing carriers, a series of actuating parts at each station, each actuating part corresponding to a support at said station, said actuating part at each station being graduated to 100 selectively actuate the load supporting parts of certain of said carriers, an unloading part at each station graduated to correspond with only certain of said carriers, means, carried 105 by said carriers and adapted to be pressed out of operative position by a load thereon, to enable an actuating part at any station to normally load a corresponding carrier from the corresponding support at such station 110 only when said carrier is empty, and means at each station to enable the unloading part at said station to actuate the load supporting part of a carrier whose graduation corresponds to said unloading part, regardless of 115 whether said carrier is loaded or not.

18. In an inter-communicating pick-up and delivery system for messages, parcels and the like, the combination of a track having a plurality of stations from which articles may be despatched and to which articles may be delivered, graduated carriers each having a movable load supporting part, 120 a series of supports at each station adapted to present articles to be despatched to passing carriers, a series of actuating parts at each station, each actuating part corresponding to a support at said station, said actuating parts at each station being graduated to 125 selectively actuate the load supporting parts 130
